REFRIGERATING APPARATUS

Filed Nov. 1, 1928

Inventor:

William A. Slager
By Chas. M. Nissen. Atty.

UNITED STATES PATENT OFFICE.

WILLEM AGE SLAGER, OF RIJSWIJK, NETHERLANDS, ASSIGNOR TO KODOWA REFRIGERATOR CO., LTD., OF THE HAGUE, NETHERLANDS, A CORPORATION OF THE NETHERLANDS.

REFRIGERATING APPARATUS.

Application filed November 1, 1928, Serial No. 318,530, and in the Netherlands August 4, 1927.

This invention relates to a refrigerating device, for instance of the absorption type, depending for its action upon the alternative evaporation and condensation of a fluid refrigerating agent.

In principle the invention is characterized by a tank mounted separately from the evaporating device, from which tank, the refrigerating agent is driven out or vaporized 10 to the evaporating device. The present system is an improvement over the usual arrangement because the location of the tank outside of the cooling space permits the dimensions of the cooling casing to be reduced 15 so that the radiation of its walls is decreased and thereby the efficiency of the refrigerating device increased.

Further according to the invention the refrigerating device may be so constructed, 20 that the refrigerating agent flows in condensed form from the condenser into the separately mounted tank. Moreover, according to the invention, the separately mounted tank may be connected by a plurality of conduits to a plurality of evaporators, while further the said conduits may be branched off from a single main or collecting conduit, coming from the tank.

The discharge from the said evaporators 30 may also be obtained by means of a plurality of conduits connected to a common return conduit, leading back to the boiler. By this arrangement, it is possible to regulate the low temperature to be produced in the cooling casing, for instance, by inserting in the conduit between the separate tank and the evaporator in the casing a throttling device which may comprise a reducing valve and which may be located within the casing and 35 may be operable from the exterior.

When using a plurality of evaporators each conduit leading to an evaporator may be provided with a throttling device. This regulation keeps the evaporation in the casing or in each casing constant, that is, it maintains a constant low temperature in the casing or casings, which is not possible in the systems now used, in which the tank is contained in the cooling space.

50 Another feature of the invention resides in the use of a single condenser for a plurality of evaporators.

In order to simplify the assembling of the various parts and to prevent leakage, the

supply conduit, i. e. the conduit between the boiler and the condenser may be located within the return conduit. In order that the invention may be more fully understood reference is directed to the accompanying drawing illustrating one embodiment of the invention.

The figure is a schematic view of the refrigerating device.

In the drawings, the numeral 1 designates a boiler, the vapor space of which is connected 65 by a conduit 2, provided with a valve 3, to a condenser 4 which in turn is connected to a reservoir or storage tank 5 through the conduit 6.

The numeral 7 denotes an evaporator in 70 the usual coil form contained within a cooling space 8. One end of the evaporator 7 is connected with the tank 5 by means of an inlet conduit 9 and a branch conduit 10 connected therewith. A regulating or throttling valve 11 connected in the conduit 10 leading to the coil is located within the cooling space with the coil and may be operable from outside of the casing by extension or connecting means, not shown.

A return or discharge conduit 12 connects with the lower end of the coil 7 with the boiler 1 through the extended part 13 of the discharge conduit having a valve 14. A conduit 15 connects the tank 5 with the boiler 85 and has its mouth positioned adjacent the bottom of the condensate in the tank so that the water may be drained into the boiler through the conduit 15 when the valve 16 is opened. The mouth of the conduit 9 is positioned well above the bottom of the tank 5 to avoid any possibility of water passing 90 from the tank 5 into the evaporator coil.

My invention is adapted to be used in connection with a plurality of evaporators as 95 well as with the single evaporator described. As shown in the drawings, the pipe 9 leading from the tank 5 may constitute a common inlet pipe for other evaporators 17 and 18 positioned in isolated cooling spaces 19 and 20 100 and provided with valves 21 and 22 corresponding to the valve 11 of the coil 10. The conduit 12 is a common outlet or discharge pipe for all the condensers and for the purpose of thermal efficiency, the pipe may surround the inlet pipe 9 throughout a portion 105 or substantially the entire length of the conduit 9.

The conduit 12 surrounding the conduit 9 terminates at intervals to permit connection of the coils with the pipe 9, the portions of the pipe 12 surrounding the pipe 9 being 5 connected by conduits 12'. These connecting conduits can, however, be omitted and the pipe 12 extend continuously along and around the pipe 9, the branch pipes to the coils in this case being cast through the pipe 12 and 10 into the pipe 9.

It will be seen that the provision of the isolated separate tank 5 makes possible a material reduction in the size of the casing surrounding the coils. These casings while illustrated as being vertically disposed may be arranged in any desired manner and positioned in separated locations.

Obviously those skilled in the art may make various changes in the details and arrangement of parts without departing from the spirit and scope of the invention as defined by the appended claims, and I therefore do not wish to be restricted to the precise construction herein disclosed.

Having thus fully described an embodiment of my invention, what I claim and desire to secure by Letters Patent of the United States is:—

1. In a refrigerating apparatus, an evaporator, a storage tank for condensed refrigerant thermally isolated from said condenser, and a conduit connecting said tank with said evaporator, said conduit being extended upwardly into said tank an appreciable distance to prevent the passage of water through said conduit into said evaporator.

2. In a refrigerating apparatus, a boiler, an evaporator, a storage tank for condensed refrigerant thermally isolated from said condenser, an inlet conduit connecting said tank with said evaporator, and a drain conduit connecting said tank and boiler, the mouth of said inlet conduit being positioned above the bottom of said tank, the mouth of said drain conduit being positioned adjacent the bottom of said tank to drain the water from said tank into said boiler.

3. In a refrigerating apparatus, the combination with an evaporator, of a boiler for re-

ceiving the refrigerant therefrom, connections 50 between the evaporator and boiler forming a circuit for conveying the refrigerant from the evaporator to the boiler, and a condenser and storage tank interposed in series between the boiler and the evaporator with connections therebetween forming a second circuit 55 between the boiler and evaporator for conveying the refrigerant from the boiler to the evaporator, said storage tank being thermally isolated from the evaporator, the first-named 60 circuit having a portion adjacent the evaporator enclosed by the second-named circuit.

4. In a refrigerating apparatus, the combination of a plurality of evaporators having a common conveying means for feeding a refrigerant to each of the evaporators and a common conveying means for conveying the refrigerant away from the evaporators, the two conveying means for conveying the refrigerant to and away from the evaporators 70 being connected in series to a boiler, a condenser and a storage tank, the latter being thermally isolated from the evaporators, and said conveying means leading to the evaporators being enclosed by the conveying means 75 leading therefrom.

5. A refrigerating apparatus comprising a boiler, a condenser, and a storage tank arranged in series, with suitable conveying means for conveying a refrigerant from the 80 boiler to the condenser and from the condenser to the storage tank, a plurality of evaporators adapted to be supplied with a refrigerant from said storage tank through a common conduit leading from said storage 85 tank to said evaporators, a plurality of means surrounding said common conduit having walls spaced therefrom to form a plurality of hollow chambers surrounding said conduit, means for connecting said hollow chambers in series to the boiler, and a conduit from each evaporator connected to one of said hollow chambers, each evaporator being connected to a different chamber.

In testimony whereof I have signed my 95 name to this specification on this 22nd day of October A. D. 1928.

WILLEM AGE SLAGER.
